UNITED STATES PATENT OFFICE.

FRANK L. PUTNEY, OF SUNSHINE, WYOMING.

GUN-SIGHT.

No. 893,751.

Specification of Letters Patent.

Patented July 21, 1908.

Application filed September 16, 1907. Serial No. 393,129.

To all whom it may concern:

Be it known that FRANK L. PUTNEY, a citizen of the United States, residing at Sunshine, in the county of Bighorn and State of Wyoming, has invented certain new and useful Improvements in Gun-Sights, of which the following is a specification.

This invention relates to fire arms and more particularly to sights therefor, and has 10 for its object to provide an adjustable sight to meet the requirements of different persons and add to the efficiency of a gun for varied use. The sight is simple and easily manufactured.

15 Other objects and advantages will be apparent from the following description, and it will be understood that changes in the specific structure shown may be made within the scope of the claims without departing 20 from the spirit of the invention.

In the drawings forming a portion of this specification, and in which like numerals of reference indicate similar parts in the several views, Figure 1 is a sectional view along the 25 barrel at the breech, of a gun bearing the present sight, Fig. 2 is an elevational view at right angles to Fig. 1, Fig. 3 is a top view of the sight, Fig. 4 is a detail of the adjusting means, Fig. 5 is a perspective view of the 30 complete sight, Fig. 6 is a sectional view transversely of a modified form of the present invention.

Referring now to the drawings, there is shown a portion of a gun barrel 7, having a 35 sight plate 8, to which there is fastened the base 9 of the present sight.

Two annular vertically extending frames 10 and 11 are mounted revolvably upon the base 9, being supported by side uprights 9', 40 the frames lying in spaced parallel relation to each other and extending longitudinally of the base. A wire 12 is carried by each frame, these wires being attached to tabs 13 carried by each frame and located diametrically opposite to each other. As shown, the corresponding tabs of the two frames are 45 spaced from each other longitudinally of the base 9, so that the wires extend at an angle to each other and in crossed relation. 50 The tabs of each frame project inwardly toward the adjacent frame, so as to bring the wires into mutual contact at their crossing point, the wires thus lying between the frames. Two transverse gears 14 and 15 55 respectively, are mounted in the base in horizontal position, the inner end portions

of the gears being in mesh. The gear 15 has an outwardly extending stem 15', which carries a milled thumb piece 16 by which the gear 15 may be rotated.

The frames 10 and 11 are provided with peripheral gear teeth 11', these teeth of the two frames being meshed respectively with the gears 14 and 15. It will thus be seen that if the thumb piece 16 be turned clockwise, the gear 15 will be revolved to turn the frame 10 counter clockwise, the gear 14 being similarly revolved. Inward rotation of the gear 14 will result in rotation of the frame 11 clockwise, so that the two frames 70 will thus be rotated in opposite directions to change the angle of the wires 12 with respect to each other. In this way, the angle of intersection of the two wires may be shifted, and the sight thus made fine or 75 coarse as desired.

In Fig. 6 of the drawings, there is shown a modified form of the invention in which a stationary frame A is mounted upon a base B. The frame is stationary, and crossed 80 wires C and D are mounted therein. It will be understood that this form of the invention is used in the same manner as the ordinary sight.

What is claimed is:

1. In a gunsight, the combination with crossed wires, of means for moving the wires relatively to change the angle of their intersection.

2. In a gunsight, the combination with 90 oppositely revolvable supporting portions, of crossed wires carried by the supporting portions, said supporting portions being movable to vary the angle of intersection of said wires.

3. In a gunsight, the combination with oppositely revolvable supporting portions, of crossed wires carried separately by the supporting portions, the supporting portions being movable to vary the angle of intersection of said wires, and means for revolving the supporting portions relatively.

4. In a gun sight, the combination with separate revolvable frames, of a wire carried by each frame, said wires being disposed in 105 crossed relation, and means for revolving the frames relatively to vary the angle of the wires.

5. In a gun sight the combination with relatively movable supporting portions, of 110 crossed wires carried separately thereby, the supporting portions being movable to vary

the angle of intersection of the wires, and means for moving the supporting portions in opposite directions simultaneously.

6. In a gun sight, the combination with 5 revoluble frames, of a wire carried by each frame, said wires being disposed in crossed relation, said frames being provided with peripheral gear teeth, gears meshed with the gear teeth of the frame said gears being in

mesh for rotation in opposite direction, and 10 means for rotating the gears.

In testimony whereof I affix my signature, in presence of two witnesses.

FRANK L. PUTNEY.
